UNITED STATES PATENT OFFICE.

CARL J. SUNDBACK, OF SALT LAKE CITY, UTAH TERRITORY.

FOLDING BED.

SPECIFICATION forming part of Letters Patent No. 431,825, dated July 8, 1890.

Application filed June 17, 1889. Serial No. 314,544. (No model.)

To all whom it may concern:

Be it known that I, CARL J. SUNDBACK, a citizen of the United States, residing at Salt Lake City, in the county of Salt Lake and 5 Territory of Utah, have invented certain new and useful Improvements in Folding Beds; and I do hereby declare the following to be a full, clear, and exact description of the invention, such as will enable others skilled in the 10 art to which it appertains to make and use the same.

My invention consists of the bedstead made in two longitudinal sections separated at the middle and pivoted on a short base, so as to 15 swing upright side by side into the form of a cabinet-case, of which the said base forms the lower part, both the sections being balanced by a spring for convenience of handling, and being adapted for ready adjustment to any 20 desired inclination of either section for the convenience of invalids, and also so that one section may be used alone for a child's bed, when required, all as hereinafter fully described, reference being made to the accompanying drawings, in which—

Figure 1 is a side elevation of the bed folded up as a cabinet-case with some parts broken out. Fig. 2 is a side elevation of the bed with one section turned down, as for a child's bed, 25 and with the end plate of the base removed. Fig. 3 is a side elevation with both sections turned down for a full-sized bed and with parts broken out to show some of the balancing apparatus, and also with the end plate of the 30 base detached. Fig. 4 is a plan of the bottom of the base, showing the balancing-springs applied to continuous rods extending from end to end of the base. Fig. 5 is a plan of a portion of the base, showing short rods for 35 the individual springs. Fig. 6 represents sections of part of one of the sections of the bedstead, illustrating more fully the balancing apparatus. Fig. 7 is a transverse section of the base and part of one of the sections of the 40 bedstead turned upright and part of the other down.

I provide a base *a*, as wide as the folded bed is to be when set up as a cabinet-case, Fig. 1, and as long as the width of the bedstead, 45 and having a standard-plate *b* near each end, but inside of the end casing *c*, and make the

bedstead of two longitudinal sections *d*, separated transversely at the middle, and pivot them to the standard-plates *b* at *e*, respectively, so as to swing up together side by side, 55 as in Fig. 1, and down either singly or both, as in Figs. 2 and 3, so that in one condition the bedstead and the base represent a cabinet-case, in another they become a child's bed, and in a third condition a full-sized bed, the 60 base being the entire support of the cabinet-case and the middle support of the bedstead, the ends of which have the folding legs *g*, which drop into the supporting condition when the bed-sections are turned down. To 65 balance the sections of the bedstead, I make them with the segmental circles *h*, having the pivot-centers *e* for their axis, and couple them by cords or chains *i* over said circles with the pulleys *j* on the spring-rollers *k*, located 70 in the base and so adjusted that as the bed-sections swing down the springs contract and allow such operation, while balancing the weight, or nearly so, according as they are adjusted, and the recoil of the springs returns the sections to the upright position with 75 a slight assistance of the operator. The segmental circles *h* are suitably grooved for carrying the chains or cords, as in Fig. 6.

The spring-rollers may extend the whole 80 length of the base and have a pulley on each end with a chain or cord *i* to each side of the bed-frame, as in Fig. 4, or short separate spring-rollers to each side may be used, as in Fig. 5.

The pulleys *j* are placed on the angular ends of the spring-rollers detachably, Figs. 2 and 3, and they are located behind the detachable end piece *c* of the base, so that they are readily accessible and detachable for 85 altering the tension of the springs whenever it may be required by turning the rollers with a wrench or key at *l*, and shifting the pulleys thereon by taking them off and turning and replacing them, which it is desirable to 90 do to alter the power of the springs according as the bed is weighted with heavier or lighter clothes or to adjust them for balancing up an invalid person in an inclined position.

By having the standards *b* of the base in- 95 side of the sides of the parts *d* two important advantages are obtained: First, the stand-

ards, which are of necessity so high as to make an objectionable appearance if outside, are concealed, and the lower end casings *c* may be placed outside instead of them to 5 represent a base finish similar to that on the front side, and thus conceal to a greater extent the indications of a bed when folded up, and, second, these end casings being removable, as above stated, expose, when taken off, 10 the pulleys *j* much more accessibly for adjustment, as above described, to vary the tension of the springs than if the standards were outside, in which case the pulleys would have to be inside.

15 When the standard *b* is made of wood, as it will generally be preferred to make it, it will be re-enforced with a metallic strip *m* to support the pivot *e*, said strip being set in flush with the surface and fastened by screws 20 *p*, and the sides of the parts *d* are similarly re-enforced with plates *n* to sustain the thrusts of the pivots. These plates *n* also have stop-studs *o*, which swing in recesses *q* of the standard, and come to rest on the upper 25 edge of the bars *m* when the sections of the bedstead reach the upright position and prevents them from passing beyond under the influence of the springs.

The base has a permanent plate *s*, extending 30 across from standard to standard, level with and occupying the space between the ends of the bottom of the bedstead-sections *d*, when turned down, on which the edges of the mattress if made in two parts or the fold if 35 made in one part, so as to double when the bed is folded up, rest when so folded up. The space thus occupied by said plate is that which necessarily exists between the said end portions of the bedstead, because of being 40 pivoted at the opposite sides of the base. In Fig. 7 this plate is represented in two separate parts, one of which is about as much higher than the other as the thickness of the plate the purpose of which is to allow the 45 lower edge of the bottom of that section of the bedstead which is the front of the cabinet-case when folded up to swing under said higher portion of plate *s* when turned down, said bottom or front being necessarily made 50 a little longer to close with the inner upper edge of the front of the base when folded up than will permit of its terminating flush with the edge of plate *s* when folded down if said part of plate *s* were in the plane of 55 said bottom when folded down. One of the sections *d* has a head-piece *t*, pivoted at *u*, so as to swing slightly with stops *v* to limit the same, and is made with cleats *w* on the lower margins to drop over the upper end of 60 the other section, as indicated in Figs. 1 and 2, to retain both parts in the upright position. In this example I represent the mode of fastening the cords or chains to the bedstead-sections *d*, above the segments *h*, to consist 65 of inserting them through the hole *x* (dotted line Fig. 6) and the recess *y* to the inside of the side piece of the bedstead and knot-

ting the end to retain it. The cords or chains can be shortened readily from time to time by adding more of the length of the knot.

I am aware of the patent to Cochrane and Kirk, No. 336,993, in which the folding end sections of the bedstead each have a bar-spring coiled flatwise at one end as a means of fastening them to the standard and connected at the other ends to the short arms of the folding sections, said springs being fastened to the standards in the axes of the folding sections without provision for and where not accessible for adjustability. My invention 80 is distinguished from the devices of this patent in that I use spring-rollers of the well-known construction adapted for ready adjustment to vary the tension of the spring and locate them in the bottom of the middle 85 section, where they are readily accessible for adjustment, which is a very necessary condition in folding beds, and being so located I connect the rollers to the folding sections by the segmental pulley and chain device intermediate to said springs and folding sections. These have no equivalent in said patent.

I am also aware of the patent to Rieckert, No. 235,293, in which a spring-roller is used of substantially the same character as mine, and connected by a strap and pulley to the short arms of the folding section of a folding bed in which the whole length folds from one side, but without the segmental pulley on the folding section. My invention is distinguished 100 from this device in that the chains of the spring-rollers are connected to the segmental pulley ends of the folding sections of the bedstead, so that while the power of the springs lessens by their expansion the leverage remains the same, and thus they hold up the folding sections better than when the leverage diminishes together with the lessening of the power of the springs.

I claim—

1. In a folding bed comprising the middle base-section and the two end sections pivoted to opposite sides thereof, the combination of the head-piece or cover with said end sections and hinged to one of them and also connected to the same by the stops limiting the opening of the cover, said cover having the cleats on the margins of the lower side closing over the upper end of the other end section to retain the two end sections in close connection in the upright position, substantially as described.
2. In a folding bed comprising the middle base-section *b* and the two end portions *d*, pivoted to the opposite sides of said middle section, respectively, and having the segmental circles *h*, of a spring-roller to each pivoted end portion and arranged side by side under the said middle base-section, cords or chains connecting said spring-rollers and segmental circles of the said end portions of the bed, and re-enforcing plates *n* on the sides of parts *d* and having the stop-studs *o*, and bars *m* on and re-enforcing standards *b* and forming

stops to the studs *o*, substantially as described.

3. The combination, in a folding bed, of the middle base-section having pivot-supporting standards located near but inside of the ends, the folding end sections having their sides exterior to said standards and pivoted to them, and also having the segmental circular ends exterior to the standards, the spring-rollers located under the base, the chains connecting said spring-rollers, and circular ends

located in the planes of said circular ends and the end casings *c* of the middle base-section exterior to the sides of the folding end sections, substantially as described. 15

In testimony whereof I affix my signature in presence of two witnesses.
